UNITED STATES PATENT OFFICE.

LOUIS E. STUCKER, OF BROOKLYN, NEW YORK.

TUBE-FORMING MACHINE.

1,130,646.

Specification of Letters Patent.

Patented Mar. 2, 1915.

Application filed May 26, 1914. Serial No. 841,089.

To all whom it may concern:

Be it known that I, LOUIS E. STUCKER, a citizen of the United States, residing at Brooklyn, in the county of Kings and State 5 of New York, have invented new and useful Improvements in Tube-Forming Machines, of which the following is a specification.

The invention relates to tube forming machines, and more particularly to the class of 10 automatically operated machines for making mailing tubes or the like.

The primary object of the invention is the provision of a machine of this character wherein the tube forming mandrel is connected 15 with a suction pump so that the suction therefrom will be utilized for gripping the sheet of paper to hold the same at one of its edges on the mandrel for the winding thereof in the formation of the 20 tube.

Another object of the invention is the provision of a machine of this character wherein in the mandrel is formed with a flange at one end so that a mandrel of any size or dimension 25 can be adapted and used in the machine.

A further object of the invention is the provision of a machine of this character wherein a tube after being formed will be ejected 30 from the mandrel, the forming of the tube and the ejecting thereof being automatically controlled.

A further object of the invention is the provision of a machine of this character 35 wherein the mandrel is formed with a flat surface provided with suction holes so that the edge of the sheet of paper can be securely held in place so as not to give the paper any chance of slipping from the 40 mandrel while the same makes its first revolution, thereby enabling the perfect formation of a tube.

A still further object of the invention is the provision of a machine of this character 45 wherein the suction pump, the mandrel, and the ejecting device, are connected through suitable transmissions or gear mechanism so as to insure the proper timing thereof in the successive operations of the same for 50 the perfect working of the machine.

Other objects will be in part obvious and in part hereinafter pointed out.

The invention accordingly consists in the features of construction, combination of elements, and arrangement of parts which will 55 be exemplified in the construction hereinaf-

ter set forth, and the scope of the application of which will be indicated in the following claims.

In the drawings:—Figure 1 is a front 60 elevation of the machine constructed in accordance with the invention, with the feed table omitted. Fig. 2 is a top plan view thereof. Fig. 3 is a rear elevation. Fig. 4 is a sectional view on the line 4—4 of Fig. 1. 65 Fig. 5 is a fragmentary longitudinal sectional view through the machine. Fig. 6 is a sectional view on the line 6—6 of Fig. 1. Fig. 7 is a sectional view on the line 7—7 of Fig. 1. 70

Similar reference characters indicate corresponding parts throughout the several views in the drawings.

Referring to the drawings in detail, the table A, legs B, and base sills C, constitute 75 the framework of the machine. Mounted upon and rising from the table A near one end thereof are spaced bearings 10 in which is supported a rotatable pipe 11, while loosely surrounding the same at its inner 80 end is a sleeve 12, to one end of which is fixed a chuck head 13, to which is detachably bolted the flanged coupling head 14 of a tube-forming hollow mandrel 15 which is disposed in alinement with the pipe 11 and 85 so that its upper peripheral portion will lie in the plane with the upper face of the table A, the said mandrel being formed at intervals with a plurality of openings 16 which extend through a flat face 17 formed thereon so that paper on the table A can be fed onto the flat face 17 to be acted upon by suction created within the mandrel 15 in a manner presently described. 90

The outer end of the pipe 11 is swiveled 95 in a stuffing box 18 mounted on the outlet end of a suction pump cylinder 19 which carries an escape valve 20 to permit the escape of air from the cylinder 19 on the instroke of the piston 21 working within the 100 cylinder, the piston being formed with the stem 22 which is pivotally connected to a throw lever 23 connected to a wrist pin 24 eccentrically mounted on a fly wheel 25 which is loose upon a counter or driven 105 shaft 26 journaled in a pair of the legs B of the framework, the said shaft being driven in a manner presently described.

Arranged on the pipe 11 are fixed and loose pulleys 27 and 28 respectively, over either 110 of which is adapted to be trained a driving belt, the fixed pulley being formed with a

clutch member 29, while splined or keyed for sliding movement on the sleeve 12 is a companion clutch member 30 for engagement with the clutch member 29 so that the sleeve 12 can be locked with the pipe 11 for simultaneous rotation therewith. Also fixed to the pipe 11 is a sprocket wheel 31 over which is trained an endless sprocket chain 32, the same being trained over a sprocket wheel 33 splined or keyed for sliding movement on the shaft 26, and this wheel 33 is formed with a clutch member 34 which is adapted to engage a companion clutch member 35 formed on the fly wheel 25, the clutch members 30 and 34 being controlled in a manner presently described. Fixed to the clutch member 30 and surrounding the sleeve 12 is a brake band pulley 36 over which is trained a hand operated brake band 37 so that the speed of rotation of the mandrel can be regulated and it be stopped at will.

Fixed to one of the outermost legs B of the framework is a guide 38 through which is passed the stem 22 of the piston working within the cylinder 19 so as to maintain the same true during the operation of the machine.

Journaled beneath the table A in the legs B and extending longitudinally of the framework is a shaft 39 on which are mounted large and small cam wheels 40 and 41 respectively, each being formed with a cam groove 42, while fixed to the cam wheel 40 is a gear 43, the same meshing with a pinion 44 fixed to an idle shaft 45 journaled in a pair of the legs B of the framework, the said shaft 45 being also provided with a gear 46 meshing with a pinion 47 fixed to the driven or counter shaft 26 so that motion from the latter will be imparted to the shaft 39.

Pivoted between its ends to the bed of the framework of the machine is a rocking lever 48, one end of which engages in the cam groove 42 in the wheel 40, while the opposite end engages in a groove 49 in the clutch member 30 so that the latter will be automatically shifted for engagement with the clutch 29, and its disengagement therefrom for the proper working of the mandrel 15 at determined intervals during the operation of the machine. Journaled in the framework of the machine parallel with and at one side of the shaft 39 is a feed shaft 50 on which is fixed a clutch member 51 disposed at one side of a companion clutch member 52 which is fixed upon an auxiliary shaft 77, the same being loosely fitted within the shaft 50, while at the opposite side of the clutch member 52 is arranged a clutch member 53, the latter being fixed to a feed pulley 54 which is loose upon the shaft 77, and to this pulley 54 is fixed one end of a feed cable 55 which is adapted to be wound thereon and unwound therefrom and is trained over a guide pulley 56 journaled in a bearing

57 fixed to one leg of the framework, and said cable has its opposite end connected to an ejector carriage 58 which is slidably mounted in the bed of the framework of the machine. The ejector arms 59 of the carriage 58 surround the mandrel 15 so as to eject a paper tube therefrom after being formed by the same. On the opposite end of the shaft is fixed a feed pulley 60 to which is connected one end of a feed cable 61, the same being adapted to be wound thereon and unwound therefrom, and is trained over guide pulleys 62 journaled in a bearing 63 fixed to another leg B of the frame-work, the opposite end of the cable 61 being fixed to the other end of the carriage 58. On the shifting of the clutch member 52 into engagement with the clutch member 51 it causes the feeding of the carriage 58 in one direction, and on the shifting of the clutch member 52 in engagement with the other clutch member 53 it causes the feeding of the carriage in a reverse direction, and in this manner the movement of the carriage to operative position and for the ejecting of the paper tube formed by the mandrel 15 therefrom are effected.

Arranged between the cam wheel 41 and the clutch member 52 and pivoted between its ends to a bracket 64 is a rocking lever 65, one end of which engages in the cam groove 42 in the said cam wheel 41, while its opposite end engages in a groove 66 formed in the clutch member 52 so that the latter will be automatically shifted for engagement with either of the companion clutch members on the shafts 50 and 77 respectively when the shaft 39 is rotated for the proper working of the ejector carriage 58 during the operation of the machine. The cam wheel 40 is loose upon the shaft 39, while the cam wheel 41 is fixed thereto and has trained thereover a belt 67, the same being trained over a pulley 68 fixed to the driven shaft 26 so that motion from the latter will be imparted to the said shaft 39. This shaft 39 carries at one end a further cam wheel 69 provided with a cam groove 70, and between the said wheel 69 and the cam member 34 is a rocking lever 71, the same being pivoted between its ends to a bracket 72 fixed to the framework of the machine, the opposite end of the lever 71 being engaged in a groove 73 formed in the clutch member 34 so that on rotation of the shaft 39 to which the arms 74 are pivoted the said clutch member 34 is automatically operated for engagement with and disengagement from the cam member 35, and in this manner the pump is intermittently operated.

Pivoted supported by the framework of the machine are the swinging arms 74 carrying a presser roller 75 which is arranged to contact with the paper when fed to the mandrel 15 so as to hold the same close thereto

for the uniform and tight wrapping of the paper delivered from the table A on to the mandrel 15, the arms 74 being actuated by means of a foot treadle 76 so that the presser roller 75 can be moved to operative or inoperative position relative to the mandrel 15 when the machine is in operation.

In the operation of the machine, assuming that the belt is running upon the loose pulley 28, and on the shifting of this belt in any suitable manner onto the fixed pulley 27 motion is imparted to the pipe 11, which rotates in the bearings 10, and through the chain connections 32 trained over the sprocket wheels 31 and 33 the counter or driven shaft 26 is simultaneously rotated therewith. Motion from the shaft 26 is imparted to the shaft 39 and through the gear connections with the cam wheel 40 which causes the automatic shifting of the clutch member 30 into engagement with the clutch member 29 so that the mandrel 15 is locked with the pipe 11 to turn therewith. However, prior to the locking of the mandrel 15 on the pipe 11 the pump becomes active, creating a suction in the mandrel 15 so that when the paper is fed from the table A onto the flat surface 17 of the mandrel 15 the suction through the holes 16 will grip and hold the edge of the paper fast to the mandrel. When the mandrel rotates the paper will be wound thereon. Uniformity and the tightness in the winding of the paper is regulated by the presser roller 75 which is actuated by the foot treadle 76. After a predetermined number of revolutions of the mandrel 15 the ejector carriage 58 is automatically operated through the cam wheel 41 controlling the clutch member 52 so that the paper tube formed on the mandrel 15 is ejected therefrom by the carriage 58 moving in one direction on the bed of the machine, thus discharging the paper tube thus formed by the mandrel 15 from the machine onto the bed thereof. When this step in the operation of the machine has been carried out the ejector carriage 58 is automatically moved in the reverse direction to normal position, and the operation of the machine is again repeated, as hereinbefore described. Fixed to the shaft 77 is a sprocket wheel 78 over which is trained an endless chain 79, the latter being also trained over a sprocket wheel 80 fixed to the shaft 45 so that motion from the latter will be imparted to the shaft 77 for the driving of the carriage in one direction.

From the foregoing it is thought that the construction and manner of operation of the device will be clearly understood, and therefore a more extended explanation has been omitted.

What is claimed is:—

1. In a tube forming machine, a hollow

perforated forming mandrel, a head on one end of said mandrel, pump mechanism having a hollow chuck detachably engaged with the head and adapted to create a suction in the mandrel, ejector means movable longitudinally of the mandrel for removing a tube formed thereby therefrom, mechanism for driving the mandrel, pump and ejector means, means operated by the last-named mechanism for reversing the direction of movement of the ejector means, a foot controlled presser roll co-operative with the mandrel, cam actuated means for stopping the mandrel at predetermined intervals, and cam actuated means for stopping the pump at determined intervals.

2. In a tube forming machine having driving mechanism, a frame having a bed, a mandrel supported above the bed, a feed table supported by the bed and arranged in the plane of the mandrel, mechanism for creating a suction in the mandrel, means for simultaneously operating the mandrel and pump, an ejector frame movable longitudinally of the mandrel and supported by the bed, a counter shaft journaled in the frame, loose and fixed pulleys on the shaft, cables each having one end fixed to the ejector frame and its opposite end fixed to one of said pulleys, a clutch member fixed to the loose pulley, a clutch member fixed to the shaft, a loose clutch member arranged between the said first-named clutch members and alternately engageable therewith, and cam means operated by the driving mechanism for controlling the loose clutch to shift the same for controlling the movement of the ejector frame.

3. In a tube forming machine having driving mechanism, a frame having a bed, a mandrel supported above the bed, a feed table supported by the bed and arranged in the plane of the mandrel, a pump, mechanism for creating a suction in the mandrel, means for simultaneously operating the mandrel and pump, an ejector frame movable longitudinally of the mandrel and supported by the bed, a counter shaft journaled in the frame, loose and fixed pulleys on the shaft, cables each having one end fixed to the ejector frame and its opposite end fixed to one of said pulleys, a clutch member fixed to the loose pulley, a clutch member fixed to the shaft, a loose clutch member arranged between the said first-named clutch members and alternately engageable therewith, cam means operated by the driving mechanism for controlling the loose clutch to shift the same for controlling the movement of the ejector frame, and a presser roller co-operative with the mandrel.

4. In a tube forming machine having driving mechanism, a frame having a bed, a mandrel supported above the bed, a feed table supported by the bed and arranged in the plane of the mandrel, a pump, mechanism

for creating a suction in the mandrel, means
for simultaneously operating the mandrel
and pump, an ejector frame movable longitudinally
of the mandrel and supported by
5 the bed, a counter shaft journaled in the
frame, loose and fixed pulleys on the shaft,
cables each having one end fixed to the
ejector frame and its opposite end fixed to
one of said pulleys, a clutch member fixed
10 to the loose pulley, a clutch member fixed to
the shaft, a loose clutch member arranged
between the said first-named clutch mem-
bers and alternately engageable therewith,
cam means operated by the driving mecha-

nism for controlling the loose clutch to shift
the same for controlling the movement of
the ejector frame, a presser roller coöpera-
tive with the mandrel, and cam operated
means for controlling the driving mecha-
nism for the starting and stopping of both
15 20
the mandrel and pump.

In testimony whereof I affix my signature
in presence of two witnesses.

LOUIS E. STUCKER.
